UNITED STATES PATENT OFFICE.

MAY PEARL BEE, OF NEW YORK, N. Y.

DESIGN FOR A HANDKERCHIEF.

Application filed July 13, 1926. Serial No. 18,346. Term of patent 7 years.

To all whom it may concern:

Be it known that I, MAY PEARL BEE, a citizen of the United States, residing at New York city, New York, have invented a new, original, and ornamental Design for Handkerchiefs, of which the following is a specification, reference being had to the accompanying drawing, forming a part thereof.

The clover leaf design is painted upon a face of the handkerchief in a color or colors contrasting with the material from which the handkerchief is made, and the plumes

at the corners are usually of a contrasting color and are formed from thin strands of silk sewed into and through the handkerchief, each plume being pressed out flat so that all plumes will normally project in the plane of the handkerchief whether the latter is folded or not.

The drawing is a plan view of a handkerchief embodying my design.

I claim:

The ornamental design for a handkerchief as shown and described.

MAY PEARL BEE.
